Primary Examiner — Robert M Spear*(74) Attorney, Agent, or Firm* — Andrew F. Young, Esq.; Lackenbach Siegel, LLP**CLAIM**

The ornamental design for an applicator dispensing head, as shown and described.

DESCRIPTION

FIG. 1 is a front right perspective view of an applicator dispensing head showing our new design.

FIG. 2 is a front elevation view of FIG. 1, the rear elevation being a mirror thereof.

FIG. 3 is a left side elevation view of FIG. 1, the right side being a mirror thereof.

FIG. 4 is a top plan view of FIG. 1; and,

FIG. 5 is a bottom plan view of FIG. 1.

In the drawings, the broken lines depict unclaimed environmental subject matter and form no part of the claim.
